TROUSERS HOLDER

Filed Aug. 15, 1930

INVENTOR

INVENTOR
Clarence G. Alexander.
BY ATTORNEY

UNITED STATES PATENT OFFICE

CLARENCE G. ALEXANDER, OF DETROIT, MICHIGAN

TROUSERS HOLDER

Application filed August 15, 1930. Serial No. 475,521.

This invention relates to trousers holders and the object of the invention is to provide a holder for trousers adapted to clamp the trousers at the cuff and at the hips and maintain a tension on the fabric to hold the trousers flat and draw out the creases or wrinkles so that the trousers will appear as though newly pressed after being in the holder for a period of time.

Another object of the invention is to provide a pair of clamp members having wire frames extending therebetween, the said wire frames being adapted to telescope and yieldable means being provided between the frames for forcing the clamp members apart.

Another object of the invention is to provide a trousers holder of the character described arranged to allow a short telescoping action of the clamp supporting frames, the said frames being also arranged to frictionally resist a complete telescopic movement thereof.

A further object of the invention is to provide a pair of clamp members each having a substantially U shaped heavy wire frame, the said frames being engaged together for telescoping action in relation to each other and the cross member of one frame being provided with elastic strips carrying hook ends adapted to be engaged over the cross member of the other U shaped frame.

These objects and the several novel features of the invention are hereinafter more fully described and claimed and the preferred form of construction by which these objects are attained is shown in the accompanying drawings in which—

Fig. 1 is a perspective view of a trousers holder embodying my invention.

Fig. 2 is an elevation showing the trousers holder as applied to a pair of trousers.

Fig. 3 is an enlarged section taken on line 3—3 of Fig. 1.

The device comprises a clamp for the trousers cuff consisting of a wood clamp member 1 and a similar clamp member 2 connected together at one end by the hinge 3. The clamp members 1 and 2 are faced on the inside with a felt facing 4 adapted to engage the trousers cuff. The clamp member 2 is

provided with a notch 5 at the end opposite the hinge 3 and a clamping member 6 is positioned in this notch and a plate 7 is secured thereover so that the member 6 may turn in the notch 5. The member 6 is shown more particularly in Fig. 3 and is provided with an extending end 8 which may be grasped in turning the member 6 from the locked to the released position. A wire hanger 9, shown in Figs. 1 and 2, is secured to the wood clamp member 1 and is provided with an eye 10 by which the device may be hung up. As shown in Figs. 1 and 2, a pair of recesses 11 are provided in the wood member 2 and a substantially U shaped frame of heavy wire or rod 65 is provided having two upwardly extending legs 12 and 13 adapted to be engaged in the recesses 11.

The lower clamping device comprises two clamp members 14 and 15 connected together at one end by the hinge 16 and being provided with a locking member 6 at the opposite ends for clamping these two members together. The lower clamp member is similar to the upper clamp member except that it is longer in order to engage the trousers at a wider point and the end of the clamp members 1 and 14 are cut on a radius as shown in order to allow the clamp member 6 to be engaged thereover.

An inverted U shaped heavy wire frame is provided with ends 17 and 18 adapted to engage in the recesses 19 provided therefor in the clamp member 15. The portion 20 of the inverted U shaped frame connecting the legs 17 and 18 is bent about the legs 12 and 13 of the other U frame at the points 21 and 22, while the cross member 23 connecting the legs 12 and 13 of the other U shaped frame is bent about the legs 17 and 18 of the inverted U frame at the points 24 and 25. By this arrangement, the U shaped frames engage and may be telescoped upon each other as they are slideable in relation to each other. As will be noted from Fig. 3, the legs 12 and 13 of the U shaped frame are provided with sloping portions 26, while the legs 17 and 18 of the inverted U frame are provided with similar sloping portions 27 and the telescoping or sliding action of the two frame mem-

bers may freely take place between the sloping portions 26 and 27.

To use the device the clamps 6 are released and the clamp members 1 and 14 are 5 swung outwardly on their hinges to allow a pair of trousers to be placed in the device. The cuff 32 of the trousers is positioned on the clamp member 2 and the clamp member 1 is turned down to engage the trousers cuff 10 and the clamp member 6 is turned to the locking position to bind the trousers cuff between the clamp members 1 and 2. The trousers are laid flat in the device with the hips of the trousers resting on the clamp 15 member 15 at which time the clamp member 14 is turned to engage the trousers between the members 14 and 15, and the respective member 6 is turned to the locking position to bindingly engage the trousers between the 20 clamp members 14 and 15.

In order to place a tension on the trousers, a pair of elastic webs 28 are secured to the cross member 20 of one frame and a hook member 29 is secured in the ends of the elastic webs 28 and is provided with a pair of hooks 30 adapted to be engaged over the cross member 23 of the other U shaped frame. When the trousers are positioned in the device, the cross members 20 and 23 are preferably spaced apart greater than the normal length of the elastic webs 28 so that it is necessary to stretch these webs in engaging the hook ends 30 over the cross bar 23. By stretching these elastic webs, the tension 35 placed thereon tends to move the clamping members at the cuff and hips of the trousers apart and maintains a tension on the fabric of the trousers which tends to take out the wrinkles or creases in the trousers except the 40 normal creases placed in the trousers by pressing. When the trousers have been thus mounted in the device, the device may be hung on a hook by means of the hanger 9 at the upper end thereof.

45 The device may be readily disassembled to be carried in a grip or suitcase by first removing the trousers therefrom. At this time, the upper clamp member may be lifted off from the ends 12 and 13 of its U shaped frame, while the ends 17 and 18 may be withdrawn from the recesses 19 in the lower clamping member. The hook ends 30 may be then disengaged from the cross bar 23 50 and the cross bars 20 and 23 may be drawn apart until the ends 12 and 13 reach the points 24 and 25 of the cross bar 23. The device is then collapsed and in compact form 55 so that the three pieces may be readily packed 60 in a suitcase.

From the foregoing description it becomes evident that the device is very simple and efficient in operation, will not easily get out of order, is very compact in form, is composed of few parts and is of consequent low

manufacturing cost and provides a device which accomplishes the objects described.

Having thus fully described my invention, its utility and mode of operation, what I claim and desire to secure by Letters Patent 70 of the United States is—

1. In a trousers holder, a pair of substantially U shaped wire frame members telescopically connected together, a trousers clamping member detachably supported on the ends of each frame member, the frame members spacing the clamping members apart, yieldable members secured to the cross portion of one U shaped frame member and a hook member carried by the yieldable members and adapted to be hooked over the cross portion of the other U shaped frame member to force the ends of the frame members apart. 75

2. In a trousers holder, a pair of substantially U shaped wire frame members telescopically connected together with the cross portion of the frame members adjacent each other, yieldable means connected to one cross portion and a hook member carried by the yieldable means and adapted to be engaged over the other cross portion and a trousers clamping member carried by the outer ends of each frame member. 80

3. In a trousers holder, a pair of substantially U shaped wire frame members telescopically connected together and freely slideable throughout a portion of their length, yieldable means tending to move the ends of the frame members outwardly, a trousers clamping member mounted on the outer ends 95 of each frame member and means resisting telescopic movement of the frame members inwardly beyond a certain point. 100

In testimony whereof I sign this specification.

CLARENCE G. ALEXANDER.
